(57) **CLAIM**

The ornamental design for an arcuate bottle, as shown and described.

DESCRIPTION

FIG. 1 is a top, front and side perspective view of an arcuate bottle showing my new design;

FIG. 2 is a front elevational view thereof, the rear view being a mirror image thereof;

FIG. 3 is a right side elevational view, the left side being a mirror image thereof;

FIG. 4 is a top plan view thereof; and,

FIG. 5 is a bottom view thereof.

The features shown in broken lines in FIGS. 1-5 are for illustrative purposes only and do not form a part of the claimed design.
